FLUID PUMP OR MOTOR

Thomas Norman Haines, Philadelphia, Pa., as
signor of one-half to Karl Legner, Rydal, Pa.

Application February 23, 1940, Serial No. 320,324

2 Claims. (Cl. 103—121)

This invention relates to a fluid pump or motor of rotary piston type and has particular reference to a type of pump or motor in which the displacement is theoretically, and in practice approximately, constantly proportional to the angular movement of the relatively rotatable elements.

It is the object of the present invention to provide a fluid pump or motor of the type just indicated which is simple in construction, silent and smooth in operation and readily repaired. The attainment of these objects and other objects of the invention, particularly relating to details of the construction, will be apparent from the following description, read in conjunction with the accompanying drawings, in which:

Figure 1 is a vertical axial sectional view through the pump or motor;

Figure 2 is a plan view of the same partly in section;

Figure 3 is a section taken on the broken plane, the trace of which is indicated at 3—3 in Figure 1;

Figure 4 is an axial section similar to Figure 2, but showing the relation of the parts following a rotation of 90° from the position illustrated in Figure 2;

Figure 5 is a fragmentary transverse section showing the relationship between certain of the parts;

Figure 6 is a horizontal fragmentary section taken on the plane the trace of which is indicated at 6—6 in Figure 5;

Figure 7 is a diagrammatic perspective view illustrating the theoretical surfaces involved in the provision of chambers of varying volumes provided in the operation of the pump; and

Figure 8 is a diagram of developed type to indicate the fashion in which the chambers vary in volume.

Before proceeding with a discussion of constructional details, reference will be made to the diagram of Figure 7, which will demonstrate clearly the applicability of the invention to the construction of either a pump or a motor, and also the wide variety of choice in the provisions of relatively movable surfaces, as it will be obvious that there are but few restrictions on the choice of physical embodiments of the apparatus.

The pump comprises, in the form illustrated in the diagram in Figure 7, inner and outer concentric spherical surfaces A and B, it being understood that the spherical surface B, merely indicated in outline in Figure 7, envelopes the various other parts illustrated in this figure to

form an outer bounding surface for various chambers to be described, the inner spherical surface A forming an inner bounding surface for these same chambers.

Opposed conical surfaces C and D are coaxial with each other and with the spherical surfaces. In this theoretical diagram, the straight line elements of these conical surfaces would intersect at the center of the spheres. (In the actual construction, as will be evident hereafter, this will not be the case, because of the thickness of a partition.) Located in an axial plane and closing off the annular region which is bounded by the spherical and conical surfaces, is a partition F which, for ease of description, may be regarded as movable with relation to the spherical and conical surfaces which, also for the sake of present description, will be regarded as fixed. In other words, this partition F will be regarded as moving in the direction of the arrow, making contact with both spherical surfaces and with the conical surface C and D at M and N, respectively.

A ring E has its inner edge engaging the inner sphere and its outer edge engaging the outer sphere so as to separate into two regions the annular space. It is tangent to the cone C at P and to the cone D at Q. The arrangement is such, consistent with the assumptions already made, that this ring E is maintained in a fixed plane passing through the center of the spheres and tangent to the cones at P and Q, respectively, but is so arranged that it may rotate about the center of the spheres, i. e., its own center in that fixed plane. The ring E is continuous with the exception of a slot at L through which extends the partition F.

Assume, now, that the partition F rotates in the direction of the arrow and in such rotation by engagement with the edge of the slot L produces a rotation of the ring-shaped partition E in the plane of the latter. Under such conditions, there are delimited within the annular space four regions the volumes of which will be varying with the movement of the partition F. One of these regions is bounded by the portion f of partition F between L and M, the portion c of the cone C between M and P, and the portion e of ring E between L and P. A second region is bounded by the portion f' of partition F between L and N, the portions e and e' of the ring E between L and Q past the tangent contact at P, and the portion d of cone D between N and Q. A third region is bounded by the portion f' of partition F, the portion e'' of ring E between L and Q, and the portion d' of cone D between

N and Q. A fourth region is located between portion *f* of partition F, portion *c'* of cone C between M and P, and portions *e'* and *e''* of ring E. As rotation in the direction of the arrow in Figure 7 takes place, it will be evident that the first two of these chambers are decreasing in volume and the latter two are increasing in volume.

The nature of the displacement which occurs will be somewhat clearer from consideration of the diagram of Figure 8, which represents diagrammatically, but without true scale representation of volumes or areas, a development of the apparatus shown in Figure 7 which may be regarded as viewing the exterior of Figure 7 in a radial direction in any point. The diagram of Figure 8 is carried out through somewhat more than 360° to illustrate the continuous nature of the displacement. In this diagram the traces corresponding to the various surfaces and the points corresponding to various lines are lettered to agree with Figure 7. Assuming that the motion to the right of the partition F, represented by the line MN, corresponds to the rotation in the direction of the arrow in Figure 7, it will be evident that the chambers described in order above are represented in Figure 8 by the regions MPL, NLPQ, QLN, PMLQ, respectively. The two regions shaded vertically are decreasing in volume. The two shaded horizontally are increasing in volume. Inlets and outlets to these chambers may be provided at X and X', and Y and Y', respectively, the inlets being on the trailing side of the partition F and the outlets on the advancing side. It will be evident, however, that the inlets may equally well be provided to the right of tangent lines P and Q, respectively, and the outlets to the left of these tangent lines, extending through the conical or spherical surfaces. It will also be evident that the partition F need not necessarily extend axially.

As will be evident from the figures, if the partitions are of infinitesimal thickness, the displaced volume is constantly proportional to the angular movement of the partition F. Slight departure from this condition arises by reason of the necessary actual thickness of the partitions in practice.

The description so far given will indicate quite clearly the freedom of design offered by the principles of the present invention. It will be evident that all that is required is a relative rotary movement between the partition F and the plane of the ring-shaped partition E. If the partition F remains stationary, the plane of the ring-shaped partition will rotate. Conversely, if this latter plane remains fixed, the partition F must rotate. Since the two spherical surfaces and the two conical surfaces are surfaces generated by revolution about a common axis, it is evidently immaterial from a theoretical standpoint whether these surfaces revolve or remain stationary. As will be evident hereafter, the guiding of the ring E for rotation in its own plane imposes as a practical condition that at least one of the spherical surfaces shall be fixed relative to the plane of the ring.

It will be further obvious that it is not strictly necessary that the surfaces be conical or spherical as described, inasmuch as, in practice, the ring E may close up the space between other surfaces provided it projects into slots formed in such other surfaces. Furthermore, the surfaces of the ring which make tangential contact with the end surfaces of the annular region may in

themselves be conical, so that the end surfaces might, for example, be planes or the end surfaces and the ring surfaces may be suitably correspondingly provided in other ways with contacting surfaces of revolution. It will be evident that such changes do not depart from the principles of the invention.

Passing to the practical embodiment of the invention in a pump or motor, it will be evident that the partition F may be fixed or rotary as mentioned above, and that, depending on the condition of this partition, the apparatus will have, practically, either a stationary or a rotary outer casing. In Figures 1 to 6, inclusive, there is illustrated a practical embodiment of the invention in which the casing is shown as rotatable. It will be evident, however, that if the casing is held stationary, then the shaft and central parts of the apparatus may be made to rotate.

Suitable standards 2 support a fixed shaft 4 on which is fixedly mounted the spherical surfaced member 6 providing the surface heretofore described at A. The shaft 4 is hollow, and in one end thereof there is the opening 8 communicating with the opening 10 in the spherical surface of 6 at one side of the partition 18. An opening 12 in the other end of the shaft 4 communicates with an opening 14 in the spherical surface at the opposite side of the partition 18. These openings are extended by slots 16 adjacent the partition 18 to secure communication with the extreme corners of the chambers. It will be evident from Figure 8 that the openings illustrated therein as very small may be connected in pairs in any suitable fashion and may be enlarged to such openings as are illustrated at 10 and 14 with their associated extension slots. Large openings are, of course, necessary to secure freedom of entrance and exit of the working fluid.

The partition 18 in the embodiment illustrated is secured to the member 6 and is provided with an outer spherical surface 20 and conical end surfaces 22 and 24, respectively. These latter surfaces engage the conical surfaces of members 26 and 28, which are rotatable upon the shaft 4, suitable stuffing arrangements being provided at 30 and 32 to prevent leakage along the shaft. These cone surfaced members 26 and 28 are pinned at 34 and 36 to halves 38 and 40 of an outer casing, which halves are provided with interior spherical surfaces having sliding engagement with the partition 18. A pulley made in halves 42 and 44 carried by the respective halves of the casing may be driven by a belt if the apparatus is used as a pump, or may drive a belt if it is used as a motor. The halves of the outer casing are provided with bearing surfaces to provide a groove 46 in which there may rotate the periphery of the ring 48 which constitutes the partition E. The arrangement is such, with respect to the conical surfaces, that this ring 48 engages such surfaces tangentially along the straight line elements of the conical surfaces.

The ring 48 is provided with a slot, indicated at 50, to embrace the partition 18. The radial edges of this slot are pointed or rounded, as indicated particularly in Figures 5 and 6, and the partition 18 is so shaped by having concave surfaces that a fluid-tight sliding fit is provided between the edges of the slot and the partition 18 for all positions of operation of the device. This shape, it will be noted, is necessary, since the plane of extent of the partition is at right

angles to the plane of the ring 48 when the parts are in the positions illustrated in Figures 1 and 2, whereas the angle between these two planes changes when the position of Figure 4 is attained to an angle such as that illustrated in Figure 4. As this angle between the planes changes, the portion of the partition 18 engaging the ring varies from end to end of the partition. It is, therefore, possible to so shape the partition to secure the desired contact in all positions of operation.

From the description previously given with respect to Figures 7 and 8, the operation of the apparatus as either a pump or motor will be evident. In the case of the particular embodiment illustrated, the spherical surface 6 and the partition 18 are stationary. The housings providing the exterior spherical surface and the conical surfaces rotate. With them there rotates the plane of the ring 48. The ring 48 merely oscillates back and forth with change of its angular position relative to the partition 18. In such operation it has, of course, a relative rotary movement with respect to the housing.

It will be immediately apparent that the housing may be stationary and the shaft 4 and its associated parts rotary, giving rise to the action which was particularly assumed in the discussion of Figure 7. In such case, the plane of the ring 48 remains stationary, and this ring rotates in its plane as driven by the partition 18. In the event that the shaft is rotated, it is not so convenient to provide for inflow and outflow of fluid through the rotating shaft. In such case, therefore, the outlets may be provided in the stationary casting. Reference to Figure 8 will make it evident that the outlets may be provided in the conical surfaces to the left of the tangent lines P and Q, while the inlets will be in the same surfaces to the right of these tangent lines.

It will be evident that a smooth operation results from the use of this apparatus, the parts being completely balanced except for the partition 18, which may be counter-balanced by providing suitable cored holes in the spherical member 6 in the event that it rotates. Uniform angular rotation takes place in the case of all the parts with the exception of the ring 48 in the case of its rotation. If the partition 18 is rotated, the ring does not have a uniform angular velocity, but will have some variations in its rotary speed, depending upon the angle of intersection with the partition 18.

What I claim and desire to protect by Letters Patent is:

1. A fluid mechanism comprising a housing providing an annular space bounded by inner and outer concentric spherical surfaces and a pair of opposed coaxial conical surfaces, said conical and

outer spherical surfaces being stationary relative to each other, a partition extending transversely of, and closing, said annular space, and secured to said inner spherical surface, the partition and inner surface being rotatable relatively to said other surfaces and the partition having surfaces bearing on said other surfaces in fluid tight fashion, a ring-shaped partition member tangent to both said conical surfaces dividing the space between said spherical surfaces, means for guiding said ring-shaped partition for rotation in its own plane relative to said outer spherical surface and said conical surfaces, said ring-shaped partition having a radially extending slot therein to pass said transversely extending partition, and the transversely extending partition having concave sides to fit in fluid-tight fashion the edges of the slot in said ring-shaped partition in all positions of the latter, the transversely extending partition and the plane of said ring-shaped partition being rotatable relatively to each other about the axis of said cones to form chambers of varying volumes bounded by portions of said spherical surfaces, said conical surfaces, and said partitions, and means providing inlet and outlet passages for fluid communicating with the chambers.

2. A fluid mechanism comprising a housing providing an annular space bounded by inner and outer concentric spherical surfaces and a pair of opposed coaxial conical surfaces, said conical and outer spherical surfaces being stationary relative to each other, a partition extending transversely of, and closing, said annular space, and secured to said inner spherical surface, the partition and inner surface being rotatable relatively to said other surfaces and the partition having surfaces bearing on said other surfaces in fluid tight fashion, a ring-shaped partition member tangent to both said conical surfaces dividing the space between said spherical surfaces, means for guiding said ring-shaped partition for rotation in its own plane relative to said outer spherical surface and said conical surfaces, said ring-shaped partition being arranged to pass in fluid-tight fashion the transversely extending partition in all positions of the latter, the transversely extending partition and the plane of said ring-shaped partition being rotatable relatively to each other about the axis of said cones to form chambers of varying volumes bounded by portions of said spherical surfaces, said conical surfaces, and said partitions, and means providing inlet and outlet passages for fluid communicating with the chambers comprising openings through said inner spherical surface extending therefrom in opposite directions along the axis of rotation.

THOMAS NORMAN HAINES.
